THE NORRIS PETERS CO., PHOTO-LITHO., WASHINGTON, D. C.

UNITED STATES PATENT OFFICE.

CARY S. COX, OF FRESNO, CALIFORNIA, ASSIGNOR TO LEE L. GRAY, OF SAME PLACE, AND THE PHOENIX RAISIN SEEDING AND PACKING COMPANY, OF FRESNO COUNTY, CALIFORNIA.

RAISIN-SEEDER.

SPECIFICATION forming part of Letters Patent No. 602,698, dated April 19, 1898.

Application filed December 31, 1896. Serial No. 617,638. (No model.)

To all whom it may concern:

Be it known that I, CARY S. COX, of Fresno, in the county of Fresno and State of California, have invented a new and Improved 5 Raisin-Seeder, of which the following is a full, clear, and exact description.

The object of my invention is to provide a raisin-seeder wherein the raisins will be received and carried by the pins to a drum and 10 be brought in engagement with a composite roller or drum so constructed that the stones of the raisins will be forced into the composite drum and retained thereby, and whereby further means will be provided for preventing 15 the stones of the raisins when delivered to the composite drum being again taken up by the raisins on the pin carrying-drum, and whereby also a means will be provided for relieving both drums or rollers of the matter 20 adhering thereto, permitting them to present clean surfaces to feed-rollers, through which the raisins containing seed are delivered for seeding.

The invention consists in the novel construction and combination of the several parts, as 25 will be hereinafter fully set forth, and pointed out in the claims.

Reference is to be had to the accompanying drawings, forming a part of this specification, 30 in which similar characters of reference indicate corresponding parts in all the figures.

Figure 1 is a longitudinal section through the machine, taken at a point near its center. Fig. 2 is a transverse section taken substantially on the line 2 2 of Fig. 1. Fig. 3 is a detail sectional view of a portion of the composite roller or drum and a portion of the pin carrying drum or roller, illustrating the manner in which the two co-operate. Fig. 4 is a 35 detail sectional view of a portion of the composite roller or drum and the comb adapted to relieve the said roller or drum from the seed adhering thereto, and Fig. 5 is a detail view illustrating the driving connection between the two feed-rollers.

A frame A is constructed of any desired shape and of any suitable material, and upon the upper portion of this frame two feed-rollers B and C are mounted, the frame being provided near its bottom with a floor 10. The

feed-roller B preferably consists of a body 11 of a non-elastic material, such as wood or metal, and an outer covering 12 of rubber or a yielding material. The journals of the feed-roller B are journaled in suitable boxes 13, 55 secured preferably upon the upper portion of the frame A. The feed-roller C, which does not engage with the yielding feed-roller B, but is located near thereto, is made entirely of a non-yielding material, and its trunnions 60 are journaled in boxes 13^a, also attached to the upper portion of the frame A. At one end of the feed-roller C a toothed wheel 14 is secured to the trunnion or shaft of the roller, and at the opposite end of the feed-roller C a 65 gear 16 is attached to the trunnion or shaft of the roller, engaging with a gear 15, secured to the shaft or trunnion of the yielding feed-roller B.

Below the non-yielding feed-roller C a raisin-carrying roller or drum D is journaled, and this roller or drum D has its periphery provided with rows of pins 17, and at one end of the trunnion or shaft of the raisin-carrying roller or drum D a gear 18 is secured, 75 which meshes with a pinion 18^a, and said pinion meshes with the gear 14 of the non-yielding feed-roller C. The shaft or trunnion of the drum or roller D is journaled in bearings 20, located, preferably, about centrally between the top and the bottom of the frame A.

The raisin-carrying drum or roller D operates in conjunction with a composite drum or roller E, which is below the yielding feed-roller B. Its shaft 22, which extends through from end to end, is journaled in suitable bearings 20^a, located on the frame in horizontal alignment with the bearing 20, as shown in Fig. 1. The shaft 22 of the composite roller 90 E has a gear 19 secured upon one end, which meshes with the gear 18 of the raisin-carrying roller or drum D.

The composite roller or drum E consists of a series of disks 23, which are mounted loosely 95 on the shaft 22, turning with said shaft, and these disks 23 are usually made with shoulders 24 at opposite sides near their peripheries and are provided with openings 25 between the shoulders and the periphery, as 100

shown best in Figs. 2, 3, and 4. The disks 23 are made usually of a non-yielding material and receive between their recessed or shouldered portions rings or gaskets 26, which 5 are made from a yielding substance, such as rubber, and the disks 23 are tightened up, so as to firmly hold the gaskets or rings 26 through the medium of lock-nuts 27 and jam-nuts 27^a, which are located on the shaft 22, 10 as illustrated in Fig. 2, and when the disks 23 are pressed closely together the yielding material of which the gaskets or rings are made will enter the openings 25 in the disks, thereby providing an additional safeguard 15 against the gaskets or rings moving from a predetermined position.

The pins or teeth 18 on the raisin-carrying drum or roller D, pass between the gaskets or rings 26, (shown in Fig. 3,) but the teeth 20 or pins 17 are of such length that ample space will be provided between their outer ends and the outer extremities of the disks 23 for the reception of the raisin-seeds.

A division or guard plate or board 28 is located between the composite drum or roller and the raisin-carrying drum or roller, as illustrated in Figs. 1 and 2, and this division board or plate extends upward to a point near where the pins of one drum enter the other 30 drum, and the upper edge of the division-plate 28 is usually more or less sharpened or beveled. The division-plate 28 may be adjusted vertically, as required, through the medium of set-screws 29, passed through the 35 floor 10, over which the division-plate is placed.

A comb is located beneath the composite roller or drum, comprising a base 30, secured on the floor 10, and teeth 31, which extend 40 between the gaskets or rings 26 to a point near the outer edges of the disks 23 of the composite drum or roller, as illustrated in Fig. 4, while a similar comb is provided for the raisin-carrying roller, being located beneath it, consisting of a base 32, secured to the floor 10 of the frame A, and teeth 33, which 45 extend between the rows of pins 17 on the aforesaid raisin-carrying drum.

In operation the raisins, through the medium of a suitable hopper or otherwise, are 50 fed between the feed-rollers B and C, and said feed-rollers deliver the raisins to the pin carrying-surface of the carrying-drum D. As the raisins on the said pin carrying-surface 55 are brought in engagement with the composite drum or roller E they are pressed against the body of the carrying-roller, while the pins tend to force the seeds from the raisins into the space between the gaskets or 60 rings 26 of the composite roller. As the latter roller revolves the seeds are removed therefrom by the comb beneath the drum, the seeds being at one side of the division-plate 28, while the comb for the carrying-roller removes the 65 seeded raisins therefrom. Thus there can be

no commingling of the seeds and the seeded raisins. Power may be applied to any one of the shafts. Usually, however, the power is applied to the shaft of the carrying-drum D.

I do not claim as new the gearing shown in 70 connection with the machine, as any system of gearing accomplishing said result may be employed instead.

Attention is called to a companion case filed January 27, 1897, Serial No. 620,927, in which 75 the toothed cylinder is also shown as acting in conjunction with a cylinder having a surface adapted to receive teeth; but the construction of the cylinder and the formation of the teeth differ from like parts shown and 80 described in the present application and drawings.

Having thus described my invention, I claim as new and desire to secure by Letters Patent—

1. In a raisin-seeding machine, a rubber-covered roller the covering of which is slotted circumferentially, substantially as described.

2. In a machine for seeding raisins, a carrying-drum for the raisins provided with pin-like projections from its periphery, and a composite drum comprising non-yielding body-disks and yielding material between the body-disks, the yielding material projecting beyond the disks, forming pockets for the reception of seed, the pin projections upon the carrying-drum being arranged to enter the spaces between the projecting portions of yielding material.

3. In a machine for seeding raisins, a drum 100 for the reception of seed, comprising non-yielding body-disks and rings or gaskets of a yielding material held between the body-disks, extending beyond said disks, forming a series of pockets for the reception of seed, 105 the said pockets having closed yielding walls.

4. In a machine for seeding raisins, a drum for the reception of seed, comprising non-yielding body-disks having openings therein, rings or gaskets of a yielding character held 110 between the disks and extending beyond them, and means for drawing the disks together and forcing the yielding material into the openings of the said disks.

5. In a machine for seeding raisins, a carrying-drum for the raisins provided with pins on its periphery, a composite drum consisting of a non-yielding body and spaced yielding projections from the periphery of the body, between which the pins on the carrying-drum 120 pass, and a division-plate located between the two drums at a point below their centers, as and for the purpose specified.

6. In a machine for seeding raisins, a carrying-drum having its periphery provided 125 with rows of pins, a composite drum consisting of a body and annular projections from the body, made of a yielding material and between which the rows of pins on the carrying-drum pass, and combs located one beneath 130

each of the drums and arranged to remove the material therefrom, substantially as described.

7. In a machine for seeding raisins, a carrying-drum having its periphery provided with rows of pins, a composite drum consisting of a body and annular projections from the body, made of a yielding material and between which the rows of pins on the carrying-drum pass, combs located one beneath each of the drums and arranged to remove the material therefrom, and a division-plate located between the combs and between the drums, extending upward to a point near where the drums come in contact, as and for the purpose set forth.

8. In a raisin-seeder, feed-rollers one of which is provided with a yielding surface, a raisin-carrying roller located beneath one of the feed-rollers and having pins located upon its peripheral surface, a composite drum consisting of a shaft and series of disks of a non-yielding material secured on the shaft, and gaskets or rings secured between the said disks and extending beyond their peripheral faces, the teeth of the carrying-drum being arranged to pass through the spaces between the gaskets or rings, and combs having their teeth arranged to enter in the spaces between

the rings or gaskets of the composite roller 30 and between the rows of teeth on the carrying-roller, as and for the purpose set forth.

9. In a raisin-seeder, feed-rollers one of which is provided with a yielding surface, a raisin-carrying roller located beneath one of the feed-rollers and having pins located upon its peripheral surface, a composite drum consisting of a shaft and series of disks of a non-yielding material secured on the shaft, and gaskets or rings secured between the said 40 disks and extending beyond their peripheral faces, the teeth of the carrying-drum being arranged to pass through the spaces between the gaskets or rings, combs having their teeth arranged to enter in the spaces between the 45 rings or gaskets of the composite roller and between the rows of teeth on the carrying-roller, and a division-plate located between the combs and between the carrying and the composite drums, the upper portion of the 50 division-plate extending to a point near where the two said drums engage, substantially as shown and described.
